LIPSTICK CONTAINER

Cyril W. Mellette, Middlebury, Conn., assignor
to Chase Brass & Copper Co., Incorporated,
Waterbury, Conn., a corporation

Application November 16, 1948, Serial No. 60,200

6 Claims. (Cl. 206—56)

1

The present invention relates in general to improvements for holders for lipsticks and the like and more particularly to holders of the general character referred to, which are adjustable for the purpose of shifting the contents of the holder, as may be required by the user.

An object of the invention is to provide a superior adjustable lipstick-holder.

A further object of the invention is to provide a superior holder for lipsticks and the like, where in a relatively-large lipstick is carried in a relatively small holder.

A still further object of the invention is to provide a superior lipstick-holder which is characterized by its economy of construction, ease of assembly and dependability of operation.

A still further object of the invention is to provide a lipstick-holder with superior operating-means characterized by a plurality of telescoping screw-threaded elements for advancing and retracting a lipstick therein.

With the above and other objects in view, as will appear to those skilled in the art from the present disclosure, this invention includes all features in the said disclosure which are novel over the prior art, and which are not claimed in any separate application.

In the accompanying drawings, in which certain modes of carrying out the present invention are shown for illustrative purposes:

Fig. 1 is an elevation of the lipstick-holder of this invention with the cap of the holder shown in section;

Fig. 2 is an enlarged front elevation of the holder of Fig. 1, with the body of the holder in section and showing the lipstick-carrier cup in an advanced position in the body of the holder;

Fig. 3 is a front elevation of the holder similar to Fig. 2, but showing the carrier-cup and operating-means therefor in section;

Fig. 4 is an exploded perspective view of the operating-means of the carrier-cup of the holder;

Fig. 5 is a transverse sectional view of the body of the holder and the carrier-cup on line 5—5 of Fig. 2;

Fig. 6 is a transverse sectional view of the holder on line 6—6 of Fig. 2;

Fig. 7 is a transverse sectional view of the holder on line 7—7 of Fig. 2; and

Fig. 8 is a transverse sectional view of a modified form of the body and carrier-cup of the holder.

Referring to the drawings, the exemplary embodiment of the invention herein chosen for illustration includes a body-member indicated gener-

2

ally at 10 consisting of a relatively-thin substantially-cylindrical metal tube open at its opposite ends and of substantially-uniform diameter throughout a major portion of its length. The portion of the body-member 10 adjacent its lower end is expanded radially slightly to form a substantially-cylindrical skirt-portion 11, the upper end of which is joined integrally to the body-member by an external circumferential shoulder 12. At substantially diametrically-opposite points adjacent the lower end of the expanded skirt-portion 11 of the body-member are formed two indented segmental beads 13, each extending at substantially right angles to the longitudinal axis of the body-member, as seen especially well in Fig. 7, for locking the body-member to the base-member of the holder as hereinafter described.

A rib 14 is struck up on the exterior of the upper portion of the body-member 10 from the inner wall thereof and extends longitudinally of the body-member from the circumferential shoulder 12 to a point adjacent the upper rim of the body-member. The rib 14 constitutes friction-means for holding the cap of the holder on the upper end of the body-member while the resulting longitudinal groove 15 formed on the inner wall of the body-member by the outwardly-struck rib 14 constitutes a keyway for preventing rotation of the carrier-cup in the body-member, as hereinafter described. The cap of the holder comprises the usual elongated substantially-cylindrical inverted cup-shaped member 16, the inside diameter of which is substantially equal to the external diameter of the body-member on a diameter which intersects the rib 14 thereof, whereby the cap is adapted to be frictionally held on the body-member for closing the open end thereof, the lower end of the cap abutting the circumferential shoulder 12 of the body-member.

The carrier-cup of the holder is indicated at 17 and comprises a relatively-shallow cup-shaped member, the external diameter of which is only slightly less than the inside diameter of the body-member 10, so as to make a close sliding fit therein. A short outwardly-projecting spline 18 is formed adjacent the upper rim of the carrier-cup and is adapted to slidingly engage in the aforesaid longitudinal recess or keyway 15 in the inner wall of the body-member thereby to hold the carrier-cup from rotating in the body-member of the holder.

The carrier-cup 17 is adapted to support a lipstick or other similar cosmetic (not shown) and to be actuated by the superior operating-means of this invention for advancing and re-

tracting the lipstick or the like in the body-member of the holder. Referring especially to Fig. 4, the carrier-cup operating-means is indicated generally at 19 and comprises three principal elements, namely, a double-threaded screw 20 formed integrally with and extending downwardly substantially perpendicularly from the underside of the carrier-cup; an intermediate externally-threaded sleeve, hereinafter referred to as a nut-member 21; and a base-member 22. The aforesaid carrier-cup and its screw 20 is preferably formed by extrusion, the threads of the screw 20 being formed by rolling or an equivalent operation and of a left-hand twist. A teat 23 is formed on the lower end of the screw and constitutes rivet-means for securing the lower end of the screw 20 within the externally-threaded nut-member 21, as hereinafter described. The nut-member 21 is preferably formed of thin sheet-metal stock and constitutes a substantially-cylindrical sleeve open at its lower end and provided at its upper end with an integral end-closure 24. The thin-walled cylindrical nut-member 21 is provided on its exterior surface with a rolled left-hand thread 25, while its end-closure 24 is provided with a vertical aperture 26 which is intersected at diametrically-opposite points on its rim by radial cuts (see Figs. 4 and 7), the portions of the end-closure 24 of the sleeve on opposite sides of each radial cut being bent downwardly and upwardly respectively to form thread-following lips 29 and 30 for threaded engagement with the screw 20 of the carrier-cup. In the present embodiment, the externally-threaded nut-member 21 is substantially equal in length to the length of the screw 20 of the carrier-cup so as to accommodate substantially the full length thereof, whereas the over-all diameter of the nut-member 21 is substantially equal in diameter to the inside diameter of the carrier-cup, whereby the externally-threaded nut-member 21 is enabled to move upwardly into the body-member of the holder for advancing the carrier-cup into its uppermost position therein, in the manner hereinafter described.

The aforesaid base-member 22 of the carrier-operating means constitutes a hollow substantially-cylindrical sheet-metal member closed at its lower end by a base-portion 31 and characterized by an operating-flange portion 32, the over-all diameter of which corresponds substantially to the over-all diameter of the skirt-portion of the body-member; and a shank-portion indicated generally at 33. The latter is formed with a pair of annular transverse vertically-spaced bearing-rings 34 and 35 which are of reduced diameter to rotatably engage the inner wall of the lower end of the skirt-portion of the body-member, and which provide an annular transverse retaining-groove 36 therebetween for reception of the two substantially diametrically-opposite indented segmental beads 18 at the lower end of the skirt-portion of the body-member, whereby the base-member is detachably secured therein but is free for rotation relative thereto. The upper end of the shank-portion of the base-member constitutes a relatively-short substantially-cylindrical internally-threaded throat 37 which is adapted to telescopingly receive the externally-threaded nut-member 21.

In assembly the operating-elements of the carrier-cup, the lower end of the screw 20 thereof is threadedly engaged with the thread-following lips 29 and 30 at the upper end of the externally-

threaded nut-member 21 and is held from moving out of the nut-member by means of a washer 38 mounted on the teat 23 of the screw 20 on the underside of the apertured end-closure 24 of the screw-threaded nut-member, the washer being fixedly secured on the teat 23 by peening over the lower end thereof, as shown especially well in Fig. 3. The lower end of the externally-threaded nut-member 21 is, in turn, threadedly engaged within the internally-threaded throat of the base-member 22. The entire operating assembly, including the carrier-cup, is then adapted to be inserted into the lower end of the body-member 15 and moved upwardly therein until the segmental beads 18 of its skirt snap into the retaining-groove 36 of the base-member. The base-member 22 is thus permitted to rotate with respect to the body-member 15 of the holder, but for normal operation is held for moving longitudinally with respect thereto.

To operate the carrier-cup for advancing a lipstick therein out of the holder, the operating-flange 32 of the base-member is turned in a right-hand direction, whereupon the externally-threaded nut-member 21 will rotate relative to the nonrotatable carrier-cup and its screw 20, thereby moving the screw and carrier-cup upwardly in the body-portion of the holder. In the present embodiment of the invention, the rotation of the nut-member relative to the screw is effected by the friction-differential between the mutually-engaging threads of the throat of the operating-flange and the nut-member 21 and the mutually-engaging threads of the screw 20 and the thread-following lips 29 and 30 of the nut-member, the frictional drag between the latter elements being less than that between the threaded throat portion of the operating-flange and the external threads of the nut-member. It will be understood, however, that equivalent means such as, for example, a pitch-differential may be used for effecting rotation of the nut-member initially relative to the screw. The vertical movement of the carrier-cup with respect to the externally-threaded nut-member 21 and the base-member 22 will continue until the washer 38 on the lower end of the screw 20 of the carrier-cup brings up against the underside of the end-closure 24 of the externally-threaded nut-member, whereupon further movement vertically of the carrier-cup and its screw 20 with respect to the nut-member is prevented. Thereafter, continued rotation of the base-member moves the externally-threaded nut-member 21 upwardly with respect to the base-member, thereby transmitting additional outward movement to the carrier-cup and lipstick. The upward movement of the carrier-cup is limited ultimately by engagement of the carrier-cup spline 18 with an inwardly-projecting shoulder 39 formed at the terminus of the keyway 15 adjacent the upper end of the body-member. Hence, further rotation of the operating-flange and the consequent threading of the nut-member 21 out of the internally-threaded throat of the base-member is prevented. To draw the carrier-cup back down into the holder, the operating-flange of the base-member is rotated in a left-hand direction, thereby initially rotating the nut-member relative to the screw 20 of the carrier-cup, in the manner hereinabove described, to retract the latter into the body-member. The retraction of the carrier-cup will continue until the base thereof engages the end-closure 24 of the nut-member, whereupon further left-hand rotation

of the operating-flange will impart similar rotation to the nut-member, to retract the latter into the base-member, thereby furthering the movement of the carrier-cup downwardly into the body-member of the holder.

Due to the telescoping relationship between the carrier-cup screw, the nut-member and the base-member of the holder, the length of travel of the carrier-cup in the holder is substantially equal to the length of the carrier-cup screw plus the length of the nut-member 21, as a consequence of which a relatively-long lipstick may be carried within a holder of relatively-short length. Moreover, due to the simplicity of construction of the carrier-cup operating-means, it is possible to employ a carrier-cup, the over-all diameter of which is substantially equal to the inside diameter of the body-member of the holder, thereby making possible the use of a lipstick of relatively-large diameter.

Although the preferred construction of the holder is as shown and described above, it will be understood that it is within the purview of the invention to include all modifications thereof within the scope of the appended claims. Thus, the upper portion of the body-member and the carrier-cup of the holder may have a substantially-elliptical form, such as shown in Fig. 8, to replace the spline and keyway construction described above, for preventing rotation of the carrier-cup in the holder; or the carrier-cup and body-member may be made hexagonal, rectangular or of other geometric shapes for effecting this purpose. Further, while but three interengaged screw-threaded elements are described in the embodiment of the invention disclosed herein, it will be understood that more than three interengaged screw-threaded elements may be used.

The lipstick-holder made in accordance with this invention is economical for manufacture, of durable and dependable operation, and is characterized by operating-means embodying substantially three principal elements threadedly engaged in telescoping relationship for effecting the movement of the lipstick-carrier cup in the holder, the simplicity of construction of the carrier-cup operating-means making the assembly and disassembly of the lipstick-holder a relatively-facile operation.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An adjustable lipstick-holder comprising a body-member having a discharge-aperture at one end; a carrier-cup mounted in said body-member, said carrier-cup and body-member being constructed and arranged to permit longitudinal movement only of said carrier-cup in said body-member to and from said discharge-aperture; carrier-cup operating-means comprising a hollow base-member having interior threads, an operating-flange and means for coupling said hollow base-member to said body-member for rotation only relative thereto; a screw projecting substantially perpendicularly from the underside of said carrier-cup; and a nut-member comprising a thin-walled sleeve having exterior threads and

an end-closure provided with thread-engaging lips, said thread-engaging lips being arranged to engage with the exterior of said screw and said exterior threads being arranged to engage with the interior threads of said base-member, said nut-member being operable by rotation of said operating-flange initially to move said screw longitudinally relative to said nut-member and thereafter to move said screw longitudinally simultaneously with the longitudinal displacement of said nut-member relative to said base-member.

2. An adjustable lipstick-holder comprising a body-member having a discharge-aperture at one end; a carrier-cup mounted in said body-member, said carrier-cup and body-member being constructed and arranged to permit longitudinal movement only of said carrier-cup in said body-member to and from said discharge-aperture; carrier-cup operating-means comprising a hollow base-member having interior threads and an operating-flange, and means for coupling said hollow base-member to said body-member for rotation only relative thereto; a screw projecting substantially perpendicularly from the underside of said carrier-cup; a nut-member comprising a thin-walled sleeve having exterior threads and an end-closure provided with thread-engaging lips, said thread-engaging lips being arranged to engage with the exterior of said screw and said exterior threads being arranged to engage with the interior threads of said base-member, said nut-member being operable by rotation of said operating-flange initially to move said screw longitudinally relative to said nut-member and thereafter to move said screw longitudinally simultaneously with the longitudinal displacement of said nut-member relative to said base-member; and rivet-means on the lower end of said screw arranged to engage with the said end-closure of said nut-member to limit the longitudinal movement of said screw relative to said nut-member.

3. An adjustable lipstick-holder comprising a body-member having a discharge-aperture at one end; a carrier-cup mounted in said body-member, said carrier-cup and body-member being constructed and arranged to permit longitudinal movement only of said carrier-cup in said body-member to and from said discharge-aperture; carrier-cup operating-means comprising a hollow base-member having interior threads and an operating-flange, and means for coupling said hollow base-member to said body-member for rotation only relative thereto; a screw projecting substantially perpendicularly from the underside of said carrier-cup; a nut-member comprising a thin-walled sleeve having exterior threads and an end-closure provided with thread-engaging lips, said thread-engaging lips being arranged to engage with the exterior of said screw and said exterior threads being arranged to engage with the interior threads of said base-member, said nut-member being operable by rotation of said operating-flange initially to move said screw longitudinally relative to said nut-member and thereafter to move said screw longitudinally simultaneously with the longitudinal displacement of said nut-member relative to said base-member; rivet-means on the lower end of said screw arranged to engage with the said end-closure of said nut-member to limit the longitudinal movement of said screw relative to said nut-member; and stop-means carried by said body-member arranged to be engaged by said

carrier-cup to limit the movement thereof outwardly from said body-member.

4. An adjustable lipstick-holder comprising a body-member having a discharge-aperture at one end and a keyway formed on the inner wall of said body-member and extending longitudinally thereof; a carrier-cup mounted in said body-member; a spline on said carrier-cup arranged to slidily engage in the longitudinal keyway of said body-member to permit longitudinal movement only of said carrier-cup in said body-member to and from said discharge-aperture; carrier-cup operating-means comprising a hollow base-member having interior threads, an operating-flange, and an annular retaining-ring, said annular retaining-ring being adapted to engage with a bead of said body-member to detachably couple said base-member thereto for rotation only relative to said body-member; an integral screw projecting substantially perpendicularly from the underside of said carrier-cup; and a nut-member comprising a thin-walled sleeve having external threads and an apertured end-closure provided with thread-engaging lips, said thread-engaging lips being arranged to engage with the exterior of said screw and said exterior threads being engageable with the interior threads of said base-member, said nut-member being operable by rotation of said base-member initially to move said screw longitudinally relative to said nut-member and thereafter to move said screw longitudinally simultaneously with the longitudinal displacement of said nut-member relative to said base-member.

5. An adjustable lipstick-holder comprising a body-member having a discharge-aperture at one end and a keyway formed on the inner wall of said body-member and extending longitudinally thereof; a carrier-cup mounted in said body-member; a spline on said carrier-cup arranged to slidily engage in the longitudinal keyway of said body-member to permit longitudinal movement only of said carrier-cup in said body-member to and from said discharge-aperture; carrier-cup operating-means comprising a hollow base-member having interior threads, an operating-flange, and an annular retaining-ring, said annular retaining-ring being adapted to engage with a bead of said body-member to detachably couple said base-member thereto for rotation only relative to said body-member; an integral screw projecting substantially perpendicularly from the underside of said carrier-cup; a nut-member comprising a thin metal sleeve having external threads and an apertured end-closure provided with thread-engaging lips, said thread-engaging lips being arranged to engage with the exterior of said screw and said exterior threads being engageable with the interior threads of said base-member, said nut-member being operable by rotation of said base-member initially to move said screw longitudinally relative to said nut-member and thereafter to move said screw longitudinally simultaneously with

the longitudinal displacement of said nut-member relative to said base-member; and rivet-means on the lower end of said screw arranged to engage with the end-closure of said nut-member to limit the longitudinal movement of said screw relative to said nut-member.

6. An adjustable lipstick-holder comprising a body-member having a discharge-aperture at one end and a keyway formed on the inner wall of said body-member and extending longitudinally thereof; a carrier-cup mounted in said body-member; a spline on said carrier-cup arranged to slidily engage in the longitudinal keyway of said body-member to permit longitudinal movement only of said carrier-cup in said body-member to and from said discharge-aperture; carrier-cup operating-means comprising a hollow base-member having interior threads, an operating-flange, and an annular retaining-ring, said annular retaining-ring being adapted to engage with a bead of said body-member to detachably couple said base-member thereto for rotation only relative to said body-member; an integral screw projecting substantially perpendicularly from the underside of said carrier-cup; a nut-member comprising a thin metal sleeve having external threads and an apertured end-closure provided with thread-engaging lips, said thread-engaging lips being arranged to engage with the exterior of said screw and said exterior threads being engageable with the interior threads of said base-member, said nut-member being operable by rotation of said base-member initially to move said screw longitudinally relative to said nut-member and thereafter to move said screw longitudinally simultaneously with the longitudinal displacement of said nut-member relative to said base-member; rivet-means on the lower end of said screw arranged to engage with the end-closure of said nut-member to limit the longitudinal movement of said screw relative to said nut-member; and a stop-shoulder at the upper end of said keyway arranged to be engaged by the spline of said carrier-cup to limit the movement of said cup outwardly from said body-member.
